YARN MEASURING MACHINE

Joseph K. Cobert, Sherbrooke, Quebec, Canada

Application March 26, 1945, Serial No. 584,822

6 Claims. (Cl. 33—147)

1

This invention relates to a yarn measuring machine and the object is to provide an accurate and reliable machine embodying intermittently operating yarn measuring means past which the yarn is moved in a step-by-step manner, the measuring means being timed to operate when the yarn is at rest and serving to measure and indicate the denier at various points along the length of the yarn.

According to the preferred embodiment of this invention the yarn is passed between stationary and movable yarn compressing elements from a supply spool to a re-winding spool which is intermittently rotated to wind the yarn thereon, the yarn being thus caused to move in a step-by-step manner past the yarn compressing elements. The movable yarn compressing element is intermittently moved toward and away from the stationary yarn compressing element so that the yarn is subjected to a constant predetermined compression pressure each time it comes to rest following an advancing movement thereof. The force acting on the movable yarn compressing element to move it toward the stationary yarn compressing element to thereby effect compression of the yarn between these elements is a constant force of predetermined magnitude. This force is applied to the movable yarn compressing element so that the distance travelled by said element during each yarn compressing movement thereof varies according to the denier of that portion of the yarn which is compressed between the yarn compressing elements. In other words, when the portion of the yarn interposed between the yarn compressing elements during the measuring operation is of minimum denier, the constant yarn compressing force acting on the movable yarn compressing element is effective to advance said element to a point substantially beyond the point to which said element is advanced by said force when the portion of the yarn interposed between said element is of maximum denier.

The denier of the portion of the yarn compressed between the yarn compressing elements during each measuring operation is indicated by a pointer which is automatically moved over a calibrated scale to an indicating position which is predetermined by and dependent on the point to which the movable yarn compressing element is advanced during its yarn compressing movement.

Proceeding now to a more detailed description of this invention reference will be had to the accompanying drawings, in which—

2

Fig. 1 is a top plan view of a yarn measuring machine made in accordance with my invention.

Fig. 2 is a side view of the machine as it appears to an observer looking in the direction indicated by the arrow X in Fig. 1.

Fig. 3 is a side view of the machine as it appears to an observer looking in the direction indicated by the arrow X' in Fig. 1.

Fig. 4 is an end view of the machine as it appears to an observer looking in the direction indicated by the arrow X² in Figs. 2 and 3.

Fig. 5 is a side view showing the two yarn compressing elements in their assembled relation. In this view the movable yarn compressing element is shown in the position which it occupies relatively to the stationary yarn compressing element when said movable yarn compressing element has been advanced to the furthest point to which it is movable by the force applied thereto.

Fig. 6 is a view similar to Fig. 5 but showing the movable yarn compressing element in a different position as compared with Fig. 5.

Fig. 7 is an enlarged view showing the overlapping yarn compressing strips of the yarn compressing elements as these strips appear when occupying the position shown in Fig. 6.

Fig. 8 is a transverse sectional view through the top portion of the main frame of the machine and through one of the holes in which the yarn compressing elements are mounted.

Figs. 9 to 12 inclusive are detail views showing a modified arrangement of the component yarn compressing strips of the relatively movable yarn compressing elements.

In these drawings the yarn being measured is indicated at 5 and is shown passing from a free-running supply spool 6 to an intermittently operated re-winding spool 7. The spool 6 (see Figs. 1, 2 and 3) is carried by a freely rotatable supporting shaft 8 removably journaled in bearing slots 9 provided in shaft-supporting arms 10 extending outwardly from the main frame 11 at one end of the machine. The spool 7 is carried by a shaft 12 removably journaled in shaft-supporting arms 13 extending outwardly from the frame 11 at the opposite end of the machine. One end of spool shaft 12 extends through a circular bearing opening 14 provided in one of the shaft-supporting arms 13. The other end of spool shaft 12 is fitted in a horizontal slot 15 extending from the free end of the remaining shaft-supporting arm 13. The last mentioned arm 13 carries a pivoted shaft retaining latch 16 which is shaped to fit over shaft 12 to retain it in the slot 15. Latch 16 is mounted to swing about a

pivotal axis 17 to either a shaft retaining or shaft releasing position and is yieldingly held in its shaft retaining position by a suitable biasing spring 18.

Spool 7 and shaft 12 are intermittently rotated in a yarn winding direction by mechanism including a substantially vertical ratchet-bar 19 engaging a ratchet wheel 20 carried by an enlarged portion 21 of the shaft 12 located between latch 16 and the adjacent end of spool 7. The lower end of ratchet-bar 19 is pivoted to one end of a cam operated lever 22 as indicated at 24 and carries a stop pin 25 working in a slightly elongated slot 26. The ratchet-bar 19 is yieldingly urged toward the ratchet wheel 20 by a spring projected plunger 26' working in a plunger casing 27 carried by lever 22. The remaining end of lever 22 is mounted to swing about a pivot 28 carried by the adjacent side member of frame 11.

A roller 29 is attached to an intermediate portion of lever 22 and rides the periphery of a lever operating cam 30 fixed to a cam shaft 31 journaled in bearings 32 carried by the side members 33 and 34 of frame 11. A cam disc 35 is fixed to a projecting end of cam shaft 31 and is equipped with a crank handle 36 whereby said shaft and disc may be turned by hand. Lever 22 is held in contact with its operating cam 30 by downward pressure exerted thereon through the agency of a spring device generally indicated at 38 in Fig. 4. This spring device comprises a plunger 39 which is projected against the top member 40 of frame 11 by a plunger projecting spring (not shown) contained in a housing 41 which is secured to lever 22 adjacent its pivotal axis.

During each complete revolution of crank shaft 31 the lever 22 and ratchet-bar 19 are raised and lowered by the cam 30 and the cooperating spring device 38. During its upward movement the ratchet-bar 19 drives the ratchet wheel 20 to rotate shaft 12 and spool 7 in a yarn winding direction. During its downward movement the ratchet-bar 19 slips past the ratchet wheel 20 without turning the spool 7. In this connection it is pointed out that spool 7 is held against casual turning movement by a friction brake generally indicated at 44 in Fig. 1. This friction brake may be of any suitable or conventional type but is here shown as comprising a spring actuated plunger 45 which is yieldingly held against one end of spool 7 by a plunger projecting spring (not shown) contained within plunger guide housing 46 attached to one of the spool shaft supporting arms 13. The plunger 45 extends entirely through the housing 46 so that its outer end 47 is accessible for manual retraction to release the braking pressure on spool 7. The engaging teeth of ratchet bar 19 and ratchet wheel 20 are shaped so that the ratchet bar is effective to rotate the ratchet wheel against the resistance of the braking pressure on spool 7 only during upward movement of the ratchet bar.

The stationary and movable yarn compressing elements between which the yarn passes during its travel from spool 6 to spool 7 are generally indicated at 50 and 51 in Figs. 1, 2, 5, 6 and 7. Each of these elements consists essentially of a group of thin metal strips 52 and 53 which are relatively long compared with their width. The component strips 52 and 53 of each element are assembled in side by side relation (see Figs. 5 to 8, inclusive) with their longitudinal axes extending horizontally and their engaging side surfaces lying in vertical planes. Strips 52 of each element are longer than the companion strips 53 and are

assembled with the latter so that the yarn-engaging ends of the strips 52 project beyond the corresponding ends of the strips 53. These projecting yarn-engaging ends of the longer strips 52 of each element are laterally separated from each other by the interposed shorter spacing strips 53 and are formed with substantially V-shaped yarn receiving notches 54. The two yarn compressing elements 50 and 51 are arranged so that, in all relative positions thereof, the notched yarn-engaging ends of the strips 52 of each element fit between and overlap the corresponding ends of the strips 52 of the companion element. This will be clearly understood from the showing of Figs. 5 to 8 inclusive.

The strips 52 and 53 of the stationary yarn compressing element 50 are mounted on one end of the top frame member 40 in a suitable box-like holder comprising side walls 56 and 57 and a bottom wall 58. The strips 52 and 53 of element 50 are thus held against lateral separation thereof and, in order to prevent longitudinal displacement of these strips, they are each provided with vertical extensions 60 which extend upwardly between and in contact with the opposing edges 61 of plates 63 and 64 which extend across the top of the box-like holder and are secured to the side walls 56 and 57 by screws 66. The holder containing the yarn compressing strips of element 50 is fitted in a channel 68 provided in the upper surface of the top frame member 40. This holder is located at one end of the top frame member 40 and is secured in place in the channel 68 so that it remains stationary at all times.

The yarn compressing strips of the yarn compressing element 51 are contained in a movable box-like holder 70 similar to that previously described. This holder 70 (see Fig. 8) comprises side walls 71 and a bottom wall 72, the latter equipped with balls 73 running on tracks 74 arranged in the bottom of the channel 68. The strips 52 and 53 of element 51 are also formed with vertical extensions 76 which extend upwardly between top plates 71 and 78 which are fastened by screws 79 to the side walls 71 of holder 70.

From the foregoing it will be seen that, in reality, each of the yarn compressing elements 50 and 51 comprises the strips 52 and 53 and the box-like holder in which these strips are arranged to prevent relative displacement thereof.

As previously stated, the elements 50 and 51 are arranged so that, at all times, the laterally separated notched ends of the long strips 52 of each element fit between and overlap the corresponding ends of the long strips 52 of the component element. However, since element 51 is mounted for movement toward and away from element 50 it will be seen that the extent to which the notched yarn engaging strips of the two elements overlap will depend upon the point to which element 51 is advanced during its movement toward element 50.

In Figs. 6 and 7 elements 50 and 51 are shown in the relative positions which they occupy prior to a yarn compressing and measuring operation. It will be noted that, in this position of the two elements the apices of the V-shaped notches 54 of the strips 52 of element 50 form with the apices of the V-shaped notches 54 of the strips 52 of element 51 the defining walls of openings 81 through which the yarn 5 passes from the spool 6 to the spool 7. When the element 50 is advanced from the position shown in Figs. 6 and 7 toward the position shown in Fig. 5 the yarn is compressed be-

tween the V-shaped ends of the two sets of strips 52 in such manner that the compression pressure is applied all around the circumference of the yarn. In practice the apices of the notched portions 54 of the two sets of strips 52 may be rounded so that the pressure of these strips will be applied to the yarn in such a manner as to retain the circular shape of the yarn. As hereinafter described the yarn compressing element 51 is moved toward the companion element 50 by the application of a force of constant magnitude so that the point to which this force is effective to advance element 51 from the retracted position shown in Figs. 6 and 7 will depend on the denier of the portion of the yarn which is subjected to compression between the notched strips of elements 51 and 52.

The application of a force of constant magnitude to the element 51 to move it in a yarn compressing direction is accomplished through the agency of a weight carrier 83 mounted to swing about a pivot 84 located at one end of the top frame member 40. This weight carrier is equipped with a pressure applying ball 84' which bears against the adjacent end of the movable holder 70 which carries the yarn compressing strips of element 51. A beam 85a is attached to and projects beyond the weight carrier 83 so that it overhangs the element 51. A weight 86 is slidably arranged on the beam 85a and may be secured in any adjusted position by a set screw 87. The weight carrier 83 is provided with an arm 88 carrying a roller 89 which rides an annular cam 90 formed on the cam disk 35. When the high portion 91 of cam 90 is in contact with roller 89 the weight carrier 83 and weight supporting beam 85a are held in the dotted line position shown in Fig. 4 and the movable holder 70 of element 51 is held in a retracted position against the ball 84' by means of a spring device 92 connected between the weight carrier 83 and a bracket 93 rising from the top plate 78 of said holder or carriage. In this position of the holder or carriage 70 of element 51 the position of the yarn compressing strips 52 of this element in relation to the corresponding strips of element 50 will be substantially as shown in Fig. 7 so that the notched ends of the two sets of strips 52 conjointly define the aforesaid opening 81 through which the yarn is passed from spool 6 to spool 7.

When cam plate 35 is rotated to move the low portion 95 of cam 90 into engagement with roller 89, the weight carrier 83 is permitted to swing about its pivot 84 under the influence of the weight 86 which exerts a turning force of substantially constant magnitude on the weight carrier. During this last mentioned turning movement of the weight carrier the ball 84' pushes against the adjacent end of the movable carriage or holder 70 of element 51 and moves this element in a yarn compressing direction so that the yarn 5 is pressed between the notched ends 54 of the strips 52 of element 51 and the notched ends 54 of corresponding strips 52 of element 50.

The distance which the holder or carriage 70 is thus advanced by the force applied through the agency of weight 86 and weight carrier 83 will depend on the denier of the portion of the yarn interposed between the notched ends of the strips 52 of the two yarn compressing elements 50 and 51. This enables the denier of the portion of the yarn compressed between the elements 50 and 51 to be measured as a function of the distance which the holder or

carriage 70 of element 51 is advanced by movement of the weight carrier 83 under the influence of the force applying weight 86.

In the present instance the arrangement 5 shown for measuring the denier of the portion of the yarn which is compressed between the yarn compressing strips 52 of the yarn compressing elements 50 and 51 includes a pointer 97 having one end arranged to travel over a suitable calibrated scale 99 carried by a scale plate 99 which is supported from the frame 11 by a suitable bracket arm 100. The scale plate 99 carries a stop 101 against which the adjacent end of the pointer 97 bears when the pointer is in its starting position.

The remaining end of pointer 97 is mounted to swing about a pivot post 97a having its lower end supported by a plate 102 and its upper end supported by a bracket 103 carried by said plate. 20 The plate 102 may conveniently be formed as an integral extension of the cover plate 63 of the box-like holder containing the strips 52 and 53 of the stationary yarn compressing element 50. The pointer 97 is connected to one end of an operating lever 105 by means of an adjustable coupling link 106. This coupling link is provided with a ball end 107 which is fitted in a ball socket 108 carried by the pointer 97 and with a second ball end 109 which is fitted in a ball socket 110 carried by the pointer operating lever 105. The ball socket 108 of pointer 97 is preferably located close to the pivot post 97a.

The end of lever 105 remote from ball socket 110 is mounted to swing about a pivot post 112 having its lower end supported by top plate 64 of the holder containing the yarn compressing strips of element 50, the upper end of said pivot post being supported by a bracket 113 carried by said plate 64.

40 The pointer 97 is normally biased to swing in a clockwise direction (Fig. 1) over the scale plate 99 by weight actuated biasing means including a flexible element 115 having one end secured to an anchoring member 116 carried by the pointer 97 and the other end secured to one end of a weight carrying arm 117, the intermediate portion of said flexible element being trained around a pulley 118 journaled in a suitable bracket 119 carried by one of the spool shaft-supporting arms 10. The weight carrying arm 117 is pivoted at 121 to a suitable pivot carrying bracket 122 attached to the side member 33 of frame 11. A weight 123 is slidably arranged on the weight carrying arm 117 and may be secured in adjusted position by a suitable set screw 124. The maximum distance travelled by the pointer 97 when moving under the influence of the biasing weight 123 is controlled by an adjustable stop screw 126 carried by a bracket 127 attached to the pointer 60 supporting plate 102.

It may be explained here that, in the normal operation of the measuring machine, the pointer 97 does not move far enough to engage the stop screw 126. The main purpose of this stop screw 65 is to prevent the pointer swinging beyond the right hand end of the scale plate 99 when, through partial dismantling of the machine or otherwise, the other pointer stop means hereinafter referred to are removed or rendered inoperative.

70 The pointer 97 is normally held in its starting position at the left hand end of scale plate 99 (Fig. 1) by means of a slidably mounted pointer-restoring member 130 which acts against the pointer operating lever 105. The pointer-restoring member 130 is arranged to slide through a 75

suitable guide 131 and has one end 132 arranged to push against the pointer actuating lever 105 when the pointer-restoring member 130 is moved to the left as viewed in Fig. 1. The end of the pointer-restoring member 130 remote from the pointer operating lever 105 is equipped with a roller 134 which rides a cam 135 formed on the cam disc 35. The roller 134 is held against the cam 135 by a spring 137 having one end anchored to a member 138 carried by the pointer-restoring element 130 and the other end anchored to a member 139 carried by guide 131. When the cam disc 35 is rotated to engage the high portion of cam 135 with roller 134 the pointer-restoring element 130 is shifted to the left as viewed in Fig. 1 and acts against the pointer operating lever 105 to swing the pointer 97 to its starting position at the left hand end of the scale 99. At this point it may be explained that in using the machine described herein the cam disc 35 is initially turned to a position such that the cams 90 and 135 act against the rollers 89 and 134 to hold the weight carrier 83 and the pointer 97 in their starting positions. The starting position of the weight carrier 83 is that indicated by dotted lines in Fig. 4 and, in this position of the weight carrier, the yarn compressing element 51 is retracted to its starting position in which the notched ends 54 of the strips 52 of this element occupy in relation to the notched ends 54 of the strips 52 of element 50 the position indicated in Fig. 7. The starting position of the pointer 97 is, as previously stated, at the left hand end of the dial plate 99.

Assuming the element 51 and the pointer 97 to be in the above mentioned starting positions, the cam disc 35 is turned through a complete revolution. The cams 90 and 135 are designed so that, during said revolution of the cam disc 35, the low point 95 of cam 90 is rotated into contact with the roller 89 thus permitting the weight 86 and weight carrier 83 to move the yarn compressing element 51 toward the yarn compressing element 50 to thereby compress the portion of the yarn 5 interposed between the notches 54 of the opposing yarn compressing strips 52. The distance which element 51 travels during its yarn compressing operation will depend on the denier of the yarn interposed between the notched ends of the two sets of yarn compressing strips 52. Shortly after the element 51 has reached the farthest point to which the weight 86 is effective to move the same, the low portion of the cam 135 is rotated into contact with the roller 134, thus permitting the spring 137 to shift the pointer-restoring element 130 to the right thereby permitting the pointer actuating lever 105 and the pointer 97 to move to the right under the influence of the biasing weight 123. During this movement of the pointer 97 to the right the element 51 is still held in its advanced position by the weight 86 and weight carrier 83. The pointer actuating lever 105 and the pointer 97 continue to swing to the right until further movement of lever 105 is arrested by engagement with an adjustable stop 141 carried by and movable with the yarn compressing element 51. As will be readily understood the position to which the stop 141 is advanced during movement of the yarn compressing element 51 under the influence of weight 86 will vary according to the denier of the yarn interposed between the yarn compressing strips 52 of the yarn compressing elements 50 and 51. Consequently, the distance which the pointer 97 travels to the right over the scale plate 99 before its further movement is

arrested by engagement of the pointer operating lever 105 with the stop 141 is directly controlled by the denier of the yarn being compressed between the yarn compressing strips 52 of elements 50 and 51.

The adjustable stop 141 could, if desired, be rigidly attached to a part of the element 51. However, I prefer to arrange the adjustable stop 141 on one end of a bar 142 having its opposite end pivoted, as at 144, to the cover plate 77 of element 51. The bar 142 carries a laterally projecting pin 146 which rides the inclined surface 147 of a cam plate 148. When the element 51 is retracted to its starting position by the cam 90 and spring connection 92 the bar 142 moves to the right with element 51 and, in so doing, is swung in an anticlockwise direction (Fig. 1) by engagement of the pin 146 with the cam incline 147, this lateral movement of the bar 142 being resisted by a spring 150 which is connected between said bar and an anchorage point on the top member 40 of the frame. Should the denier of the yarn be such that the yarn compressing movement of element 51 is stopped before it reaches the position shown in Fig. 1, the pin 146 will be engaged by a higher portion of the cam 147 so that the stop carrying arm 42 will be held in a position at an angle to that shown in Fig. 1 and the stop 141 will be positioned to retard the time of contact between said stop and pointer operating lever 105.

Shortly after the indicating movement of the pointer 97 is arrested by the stop 141 the cams 90 and 135 operate to restore element 51 and pointer 97 to their starting positions. Following this and during the same revolution of cam plate 35 the cam 39 on shaft 31 operates the lever 23 and ratchet-bar 19 to effect a predetermined turning movement of spool 7 in a yarn winding direction, thus causing a new length of the yarn 5 to be drawn into place between the yarn compressing elements 50 and 51 for the next measuring operation.

The end of shaft 31 remote from cam disc 35 carries a disc 153 provided with a V-shaped notch 154 in which the V-shaped end 155 of a spring projected plunger 156 is received each time the shaft 31 completes a full revolution. Plunger 156 is mounted in a casing 157 containing a plunger projecting spring 158.

When the machine described herein is used for measuring very fine yarns the accuracy thereof may be improved by substituting for the previously described yarn compressing means the modified yarn compressing means shown in Figs. 9 to 12 inclusive. The modified yarn compressing means comprises two groups of thin metal strips 52a which are used in place of the previously described strips 52 and 53. The strips 52a of each group are of the same overall length and are provided with straight diagonally inclined yarn-engaging end edges 52b. The inclined end edge 52b of each strip is oppositely inclined with respect to the inclination of the corresponding end edge of the next adjacent strip or strips contained in the same group. In this connection it will be noted that the inclined end edges of adjacent strips in the same group conjointly provide the sides of a V. It will also be noted that the yarn-engaging ends of the component strips of each group overlap the corresponding ends of the component strips of the companion group as clearly shown in Fig. 12. It will also be noted that the strips of each group are in flat engagement with each other thereby eliminating the previously described spacers 53.

Having thus described what I now conceive to be the preferred embodiment of this invention it will be understood that various modifications may be resorted to within the scope and spirit of the invention as defined by the appended claims.

I claim:

1. In yarn measuring apparatus of the character described, a frame structure, opposed stationary and movable yarn compressing elements mounted on said frame structure, each element comprising a holder including bottom and side walls and top plates extending between and secured to the side walls with the inner edges of the plates spaced apart to define an intervening slot and a group of thin yarn-engaging strips arranged in side by side relation in the holder in direct contact with each other and with the side walls of the holder, each strip being provided with a projection extending upwardly through said slot and being also provided, at its inner end, with a yarn-engaging face complementary to an opposing yarn-engaging end face of the corresponding strip of the opposing yarn compressing element.

2. Yarn measuring apparatus as set forth in claim 1, including means for moving the movable yarn compressing element to a yarn compressing position in the direction of the stationary yarn compressing element and then moving the movable yarn compressing element to a yarn releasing position away from the stationary yarn compressing element, a stop member carried by the holder of said movable yarn compressing element, a scale plate, a pointer arranged to travel over said scale plate from a starting position to an indicating position predetermined by the position to which said stop is advanced by the yarn compressing movement of said movable yarn compressing element, a member attached to and movable with said pointer in the path of said stop and engageable with said stop to predetermine the indicating position to which the pointer is moved in accordance with the position to which the stop has been advanced when engaged by said member, biasing means normally tending to move the pointer over the scale plate from a starting to an indicating position, and pointer controlling means operable to retain the pointer in its starting position during movement of the movable yarn compressing element to its yarn compressing position and to release the pointer for movement to an indicating position under the influence of said biasing means when the movable yarn compressing element has reached the end of its travel in a yarn compressing direction.

3. Yarn measuring apparatus as set forth in claim 1, including a rotatable shaft, a pair of cams carried by and rotatable with said shaft, means controlled by one of said cams for shifting the movable yarn compressing element to a yarn compressing position in the direction of the stationary yarn compressing element and then shifting the movable yarn compressing element to a yarn releasing position away from the stationary yarn compressing element, a stop member carried by the holder of said movable yarn compressing element, a scale plate, a pointer arranged to travel over said scale plate from a starting position to an indicating position which is predetermined by the position to which said stop member has been advanced at the end of the yarn compressing movement of the movable yarn compressing element, a member attached to and movable with said pointer in the path of said stop and engageable with the stop to predeter-

mine the indicating position to which the pointer is moved in accordance with the position to which said stop member is advanced at the end of the yarn compressing movement of the movable yarn compressing element, biasing means normally tending to move the pointer over the scale plate from a starting to an indicating position and pointer controlling means operable to retain the pointer in its starting position during movement of the movable yarn compressing element to its yarn compressing position and to release the pointer for movement to an indicating position under the influence of said biasing means when the movable yarn compressing element has reached the end of its travel in a yarn compressing direction, said last mentioned means being controlled and actuated by the other of said cams.

4. Yarn measuring apparatus comprising opposed stationary and movable yarn compressing elements between which the yarn is pressed during each measuring operation, force applying means arranged to shift the movable yarn compressing element to a yarn compressing position in the direction of the stationary yarn compressing element by the application of a force of predetermined constant magnitude so that the distance travelled by said movable yarn compressing element during each yarn compressing movement thereof varies according to the denier of that portion of the yarn which is interposed between the yarn compressing elements, means for shifting the movable yarn compressing element to a yarn releasing position away from the stationary yarn compressing element and against the resistance of said force applying means after the movable yarn compressing element has reached the end of its travel in a yarn compressing direction, a stop member carried by and movable with said movable yarn compressing element, a scale plate, a pointer arranged to travel over the scale plate and means for operating and controlling the pointer so that it is held in a starting position during the yarn compressing operation, is moved over the scale plate at the end of the yarn compressing operation to an indicating position which is predetermined by the position to which said stop member has been moved at the end of the yarn compressing operation and is returned to starting position simultaneously with the movement of the movable yarn compressing element to its yarn releasing position, said last mentioned means including biasing means acting against the pointer to move it from its starting position to an indicating position, means for holding the pointer in its starting position against the resistance of said biasing means during the yarn compressing operation and means for rendering said holding means ineffective upon completion of the yarn compressing operation to thereby release the pointer for movement to an indicating position under the influence of the biasing means and a member attached to and movable with the pointer and engageable with said stop member to bring the pointer to rest when it has travelled a distance predetermined by the position of the stop member at the end of the yarn compressing operation.

5. Yarn measuring apparatus comprising stationary and movable yarn compressing elements, means for shifting the movable yarn compressing element to a yarn compressing position in the direction of the stationary yarn compressing element, means for shifting the movable yarn com-

pressing element to a yarn releasing position away from the stationary yarn compressing element when the yarn compressing operation is completed, a stop member carried by and movable with the movable yarn compressing element, a scale plate, a pointer mounted to swing about a pivotal axis located at one end thereof and having the other end arranged to travel over said scale plate from a starting position to an indicating position and vice versa, biasing means acting against the pointer to move it over the scale plate from its starting position to an indicating position, a lever having one end mounted to swing about a pivotal axis and having the other end attached to the pointer, said lever being engageable with said stop member to predetermine, in accordance with the position of the stop member at the end of the yarn compressing operation, the indicating point to which the pointer is moved over the scale plate, a movable pointer resetting member engaging said lever, means operable during the yarn compressing operation to maintain the pointer resetting member in a position where it acts against said lever to hold the pointer in its starting position against the resistance of said biasing means, said last-defined means being operable, upon completion of the yarn compressing operation, to effect shifting of the pointer resetting member in a direction away from said lever whereby the pointer is released to move to an indicating position under the influence of said biasing means.

6. Yarn measuring apparatus comprising stationary and movable yarn compressing elements, a pivotally mounted member bearing against and connected to the movable yarn compressing element, biasing means acting against said member to swing it about its pivotal axis in one direction to thereby shift the movable yarn compressing element to a yarn compressing position in the direction of the stationary yarn compressing element, a rotatable shaft, a cam carried by said shaft and engaging a part of said member, said cam operating during a part of

each revolution of the shaft to swing said member in the opposite direction about its pivotal axis to thereby shift the movable yarn compressing element to a yarn releasing position away from the stationary yarn compressing element and against the resistance of said biasing means, a stop member carried by and movable with the movable yarn compressing element, an indicating pointer, biasing means acting against the pointer to move it from a starting to an indicating position and means whereby said pointer is held against movement under the influence of the pointer biasing means during the yarn compressing operation and is released to move under the influence of said biasing means upon completion of the yarn compressing operation, said last mentioned means including a second cam on said shaft, a lever attached to and movable with said pointer and engageable with said stop and a slidably mounted pointer resetting member arranged with one end acting against said lever and the other end acting against said last mentioned cam.

JOSEPH K. COBERT.
